UNITED STATES PATENT OFFICE.

HENRY LUND SMITH, OF PATERSON, NEW JERSEY.

SWIMMING HARNESS.

1,423,638.

Specification of Letters Patent.

Patented July 25, 1922.

Application filed June 7, 1921. Serial No. 475,655.

To all whom it may concern:

Be it known that I, HENRY LUND SMITH, a citizen of the United States, residing at Paterson, in the county of Passaic and State 5 of New Jersey, have invented certain new and useful Improvements in Swimming Harness, of which the following is a specification.

The object of this invention is to provide 10 a device which will be helpful in swimming or learning to swim in that it will afford support to the user's head and keep his mouth above water without exerting any direct buoying effect on any other parts of 15 his body, which are to be left quite as free as if any means for assisting in swimming were not present.

My invention is to be distinguished from 20 so-called "water-wings" and devices of that class proposed for use in assisting to swim which act to buoy up the user's torso but leave his head free to drop forward and hence his mouth to be submerged. It is also to be distinguished from mere life 25 preservers which by affording artificial buoyancy at the back as well as at the front of the wearer, usually fitting around his neck, simply keep him upright, with his head above water, and in fact interfere with 30 his taking any of the conventional positions for swimming.

The invention contemplates the employment in swimming harness of a buoyant member to fit under the wearer's lower jaw 35 and girdling means to secure said member in that position. Said member according to my invention in its best form is elongated and shaped so as to taper toward both ends, thus to fit partially about the neck, and with 40 its mid-portion flattened so as to appear vertically elongated and preferably inverted pear-shaped in section. Practical experiments have shown that this form is very desirable because, while permitting the device to have adequate bulk for supporting 45 the wearer's mouth above water, it avoids undue forward projecting thereof which would be a source of actual embarrassment if not an impediment in swimming and so 50 detract from the principal function of the device in assisting a learner to swim and besides cause the device to work up past the chin unless held unduly tight about the neck. Moreover, as will appear, the flat- 55 tening results in the lowest portion of the member when in place lying close to the

wearer, and so it affords at said portion a point of connection for a part of the girdling means which extends under the arms of the wearer that is very advantageous in 60 keeping the said member from working out of place.

The buoyant member may be made buoyant by being inflated or in any other way.

In the accompanying drawings, 65 Figure 1 is a front elevation of the harness;

Figure 2 is a side elevation of the buoyant portion of the harness;

Figures 3 and 4 are sections on the lines 70 3—3 and 4—4, respectively, of Figure 1; and

Figure 5 shows the harness in position on the wearer.

a designates the member to fit under the 75 wearer's lower jaw, the same being a bulb of flexible material, such as a suitable fabric impregnated with rubber, and being inflated. For the purpose of inflating this member when the harness is put in use it 80 may have a valve device *b* of well known type in which the closing member or valve proper seats outwardly in closing or sealing when the interior pressure becomes greater than the exterior pressure. This member *a* 85 is elongated and tapers toward both ends; it will be preferable also to give it a permanently curved shape as shown in Figures 1 and 5 so that it conforms more or less to the wearer's neck. It is further preferable 90 that when it is in place it conform more or less to the profile of the wearer's neck, and for this reason it is curved at the inner side (marked *c* in Figure 3) as seen in vertical cross section. Also, as seen in vertical sec- 95 tion and as to its mid-portion, it is flattened, i.e., vertically elongated, being preferably inverted pear-shaped, the advantages of which have been already stated.

The girdling means in the illustrated ex- 100 ample includes two principal members. One is a pair of straps *d* *d* each having one end suitably secured to the ends of the member *a* and said straps being adapted to have their ends secured together at the back 105 of the wearer's neck, as by a buckle or clasp *e*. The other is a bandage member embodying in the present example a triangular breast portion *f* which is secured at its top edge in some suitable way to the 110 front lowest portion of member *a* (which, on account of the described form of the

member, lies close to the wearer's body, at the base of the neck, when the member is in place), and has extending laterally from its lower part the opposite straps *g*, which are passed under the wearer's arms and tied or otherwise secured together at the back.

Whatever the construction and manner of arranging the girdling means it should be of such a character that when the device 10 is in use the girdling means will insure member *a* being held permanently under the wearer's lower jaw, as shown in Figure 5. I find the girdling means shown, and including means to be passed and secured 15 around the wearer's neck to thus draw or bring member *a* under the lower jaw and means adapted to be passed and secured around the wearer's body below the arms and attached to the member at its aforesaid 20 front lowest position to thus keep the member *a* from working laterally one way or the

other out of place, to be well adapted for this purpose.

It will be understood that in conformity 25 with my object herein set forth the girdling means shown is relatively non-buoyant.

Having thus fully described my invention, what I claim as new and desire to secure by Letters Patent is:

Swimming harness including an elongated member tapered toward both ends and having its mid-portion flattened and adapted to bear flat against the wearer's throat and up against his lower jaw and girdling means attached to said ends of the 30 member and also to the lowest part of its said mid-portion and adapted to extend around the wearer to hold said member flat against his throat.

In testimony whereof I affix my signature. 40

HENRY LUND SMITH.
